UNITED STATES PATENT OFFICE.

OSCAR KAFKA, OF NEW YORK, N. Y.

COLLAR.

1,170,972.

Specification of Letters Patent.

Patented Feb. 8, 1916.

Application filed January 13, 1915. Serial No. 1,897.

To all whom it may concern:

Be it known that I, OSCAR KAFKA, a citizen of the United States, residing at New York, county of Bronx, and State of New York, have invented certain new and useful Improvements in Collars, of which the following is a full, clear, and exact description.

The object of the invention is to provide a turn-down collar of improved construction which will overcome the difficulties heretofore experienced in adjusting or tying a cravat in desired position in a collar when in place about the neck of the wearer. This difficulty has been due to a binding or frictional engagement between the collar and cravat and often resulted in damage to the collar, cravat, or the shirt upon which the collar is secured. The objection is so pronounced that scarf manufacturers have devised various designs of ties or scarfs which are alleged to slip easily between the inner and outer band of the ordinary turn-down collar, chief among which are those whose portions contacting with the collar are provided with a fabric that will cause the minimum amount of friction between the scarf and collar when the former is placed in position on the latter. It is recognized, even with scarfs best designed for this purpose that they do not satisfactorily overcome this difficulty, especially with certain types of collars or with collars that have not been properly laundered. With my invention it is immaterial as to how the scarf is manufactured as in any event the frictional engagement of the scarf between the inner and outer folds of the collar is substantially overcome and a free and easy slip of the scarf is thus permitted.

The use of my invention is particularly advantageous in connection with collars containing the well known "arrow notch", for if force is required to draw the cravat to the point of adjustment this notch is quite likely to slip off of the collar button.

Preferred embodiments of the invention are illustrated in the accompanying drawings, in which—

50 Figure 1 is a perspective view of an ordinary turn-down collar with my improvement illustrated therein. Fig. 2 is also a perspective view of a turn-down collar showing a modification of my invention.

55 Any desired style of turn-down collar may be used and in the drawings the outer por-

tion or flap of the collar is indicated by 1 and the inner portion or neck band is indicated by 2. The usual button holes are provided at the front and rear of the neck band 60 to secure the same to the shirt of the wearer.

In the neck band of the collar tongues 3 are formed by cutting the band, and at the upper or inner end of the tongue thus 65 formed the band is cut away forming an opening 4. The tongue is adapted to be pressed toward the outer flap 1 and to be positioned between the cravat and this outer flap when the cravat has been inserted in 70 place in the collar. It remains in this position so long as the cravat is retained in the collar. The openings 4 at the upper end of the tongue are designed to receive the edge of the cravat and to permit the same to be 75 moved therethrough freely. In this connection it is to be noted that it is immaterial whether the opening or space at the inner end of the tongue is extended downwardly a considerable distance, even to the bottom 80 of the band, provided, however, a requisite space is allowed at said inner or upper end thereof.

The described arrangement eliminates the objection heretofore experienced from friction, which was due to the outer flap bearing against the cravat causing it to engage frictionally with the neck band when it was desired to draw the cravat through the collar. In my collar the tongue, which is 85 placed between the outer flap and the neck band, receives any pressure from the outer flap and prevents it from frictionally engaging the same in the manner related above. Consequently a cravat may be drawn 90 through this improved collar without the inconvenience heretofore experienced.

The length of the tongue is preferably determined by the width of the ordinary cravat at the part thereof which is designed 100 to fit in the collar, and in the accompanying drawings the preferred length is illustrated. The particular advantage of this arrangement, is that the cravat is retained in proper position and not permitted to 105 move upwardly out of desired position.

In Fig. 1 the tongue extends to the lower edge of the neck band, but in the modification illustrated in Fig. 2 the tongue 3 does not extend through the lower edge of the 11 neck band. In practice, I prefer to apply two tongue members in the neck band and

to place the same in the part of the collar fitting at the back of the neck of the wearer and on opposite sides of the usual button hole designed to secure the collar in adjustment at the back.

It will be understood of course that my invention is not limited to the precise structure illustrated and described but other embodiments may be made all coming within 10 the invention.

What I claim is:

1. A turn down collar provided with an inner and outer fold having center and end button-holes in the inner fold, in combination with downwardly projecting tongues formed in the inner band adjacent the center button-hole at the back of the collar adapted to be normally positioned between the cravat and the outer fold, the edges of said 15 tongues and the edges of the inner band adjacent thereto defining openings through 20

which a portion of the cravat is adapted to pass, whereby free and easy slip of said cravat between said folds is effected.

2. A turn down collar provided with an 25 inner and outer fold having center and end button-holes in the inner fold, in combination with downwardly projecting tongues formed in the inner band adjacent the center button hole at the back of the collar adapted to be normally positioned between the cravat and the outer fold, the said inner 30 band having openings therein at the upper ends of the tongues to receive the edge of the cravat as it is drawn through the collar. 35

In testimony whereof I affix my signature in the presence of two subscribing witnesses.

OSCAR KAFKA.
